VANITY CASE AND ATOMIZER

Filed Nov. 19, 1946

UNITED STATES PATENT OFFICE

2,469,267

VANITY CASE AND ATOMIZER

Stanley Hutt, Washington, D. C., and Robert H. Symonds, Arlington, Va.

Application November 19, 1946, Serial No. 710,841

5 Claims. (Cl. 132—79)

1

The present invention relates to a vanity case, particularly to a vanity case which is adapted to contain a perfume dispensing means in addition to the usual contents of such vanity cases.

It is one object of the present invention to provide a vanity case of this character which is simple in construction and operation and which may be manufactured at low costs.

Another object of the present invention is to provide a vanity case of this character with improved sealing means to prevent leakage or evaporation of the liquid contents when the liquid dispensing means are not in use.

The nature of the invention will be better understood from a description of a particular illustrative embodiment thereof, for the purpose of which description reference should be had to the accompanying drawing forming a part hereof and in which

Figure 1 is a perspective view of the vanity case constructed in accordance with the invention.

Figure 2 is a top plan view with the lid open and partially in section.

Figure 3 is a transverse vertical section taken on lines 3—3 of Figure 2 looking in the direction of the arrows.

Figure 4 is a transverse vertical section taken on line 4—4 of Figure 2.

Figure 5 is a fragmentary horizontal sectional view of a portion of the casing showing more particularly the arrangement of the bellows and the co-acting nozzles, and

Figure 6 is a transverse vertical section taken on line 6—6 of Figure 2 showing more particularly the interior of the compartment holding the liquid perfume and the nozzle section associated therewith.

Referring more particularly to the drawing, 10 designates a casing of metal or other preferred material. This casing 10 is provided with a vertical partition 11 which extends the entire length of the casing and a second vertical partition 12 which extends from the vertical partition 11 to an end wall 13 of the casing 10. As thus described, this arrangement of partitions divides the casing 10 into a large compartment 14 adapted to contain the usual contents of a vanity case such as powder, lipstick, powder puff, etc., and smaller compartments 15 and 16.

A lid or cover 17 carrying the usual mirror 18 is provided to enclose the contents of the vanity case.

The compartment 16 is provided with a bellows 19 which may be of rubber or other preferred material. This bellows is preferably bonded to

2

the bottom of compartment 16 and is provided with a metallic pressure pressure plate 20 which is also suitably bonded to the bellows. The bellows 19 and pressure plate 20 are provided with a vent 21 for a purpose to be described later. It will be noted that the pressure plate 20 does not extend beyond the top surface of the bellows and that by reason of the bond between the bellows and the casing there is no shifting of the bellows within compartment 16. It will further be noted that when the bellows is in extended position, such as shown in Figure 3, it does not project beyond the walls of the compartment 16.

The second small compartment 15 is utilized to contain the liquid or perfume to be dispensed; and such compartment is provided with a closure plate 22, which is best shown in Figure 4, and a filler cap 23, for the purpose of replenishing the supply of perfume in the compartment 15. The end wall 13 of the casing, which also forms one wall of the perfume compartment 15, is provided with a reentrant wedge shaped portion 24.

The bellows 19 has suitably connected thereto a nozzle 25, which nozzle projects through an opening 26 in the partition 12, and through one wall of the wedge portion 24. It will be noted that the projecting part of nozzle 25 is housed within the space formed by portion 24, and does not extend up to or beyond the casing wall 13. A second nozzle 27 is positioned in the perfume container compartment 15 and may be secured by a small clamp 28 welded to the casing and enveloping the nozzle 27. It will be noted that this nozzle 27 is provided with a bell mouth 29 and that in the dispensing position shown in Figure 2, this bell mouth rests on the bottom of the perfume container 15, whereby substantially all of the perfume may be dispensed from this compartment 15. The other end of the nozzle 27 projects through the other wall of the wedge shaped portion 24 and lies spaced from nozzle 25 but within the housing formed by the walls of portion 24. A vent opening 30 is provided in one portion of the V-shaped housing 24 for the purpose of venting the perfume compartment 15. It will be understood of course that the nozzle connections such as through opening 26, and through openings in the wedge housing, are suitably soldered or otherwise secured at these portions to provide leak-proof connections.

The lid or cover portion 17 of the vanity case is provided with sealing means 31 which may be of rubber or any other preferred material. It

will be noted that this sealing means is of wedge shape or of a shape corresponding to the shape of the reentrant portion 24, and that when in closed or sealing position, the rubber pad 31 not only seals the ends of nozzles 25 and 27, but also seals the vent opening 30. When the cover 17 is closed to seal off the nozzles and vent, the action of closing the lid results in a shear action to seal the nozzles.

In use, the compartment 15 is filled with perfume through the filler cap 23. When it is desired to dispense perfume, the cover 17 is first opened to the position shown in Figure 1, and the pressure plate 20 is depressed or otherwise actuated to force air from the bellows to nozzle 25, which action results in the atomization of the perfume which is picked up from the tip of nozzle 27. The vent opening 30 is for the purpose of entrapping or for receiving air from the atmosphere, but of course the nozzle 25 could serve a similar function.

The sealing means 31 are preferably bonded to the cover portion 17 by any well known metal to rubber adhesives and this is also true of the bond between the bottom of the compartment 16 and the bottom of the bellows 19 and the bond between the pressure plate 20 and the top of the bellows 19.

With reference to the sealing pad 31, it will be noted that this comprises a block of rubber of substantially wedge shape. As such, this pad is provided with beveled sides and a flat bottom. When the lid 17 is closed over the container 10 the sealing pad enters the depressed portion 24 of the perfume container 15 with a wiping or shearing action of its bottom over the outlets of nozzles 25 and 27 which are housed in the depression 24. The pad 31 is of a size and shape to fit within the depression 24 and the beveled sides of the pad 31 mate with the sloping walls of the depression 24. The apex of depression 24 serves to receive in each of its side walls the projecting or dispensing ends of the nozzles 25 and 27 and, of course, the pad 31 does not extend or project beneath the outlet ends of nozzles 25 and 27. The bottom of the pad 31 seals or closes off the ends of the nozzles while one of the beveled sides of the pad serves to seal the vent 30 in the corresponding wall of the depression 24.

The closure plate 22, which together with partition 11, side wall 13 and the top wall of casing 10 forms the enclosed perfume container 15, is soldered to parts 10, 11 and 13 to provide a liquid proof compartment. The perfume dispensing position of the present invention is preferably that shown by Figure 2. In this position, the bell mouth 29 of nozzle 27 lies at the lowest position of the contained perfume and permits the entire contents of the container 15 to be dispensed.

It will be noted that the nozzles 25 and 27 diverge from their outlets positioned in housing 24 to their respective inlets, that is, the inlet to the bellows and the inlet 29 to the perfume. The nozzle 27 in addition to its diverging portion is provided with a vertical portion adjacent the top wall of casing 10 and a horizontal portion terminating in a bell mouth 29 which lies substantially midway of the perfume container partition 11. This arrangement of the nozzle 27 serves to slow up the passage of perfume to the outlet end thereof and results in a better atomization in conjunction with the air issuing from nozzle 25.

It is to be understood that changes may be made in the construction and the combination and arrangement of the several parts, provided

that such changes fall within the scope of the appended claims.

What we claim is:

1. A cosmetic container comprising a casing 5 adapted to contain toilet articles, an open compartment in said casing, a bellows secured in said compartment, a closed compartment adjacent said open compartment adapted to contain liquid perfume, a re-entrant portion in said closed 10 compartment, a nozzle secured in said closed compartment in communication with the perfume therein and having its outlet end located in said reentrant portion, a second nozzle operatively secured to said bellows and having its outlet end 15 located in said reentrant portion in spaced relation to the outlet end of the first nozzle, a hinged closure for said casing adapted when opened to externally expose said nozzles, and means carried by said closure to seal the outlets 20 in said reentrant portion when said closure is in closed position.

2. A cosmetic container comprising a casing, a partition within said casing from the top to the bottom wall thereof, a second partition within 25 said casing from the first mentioned partition to a side wall of the casing, said partitions forming said casing into a large and two smaller compartments, a cover united to the walls forming one of the smaller compartments to enclose said 30 compartment, a filler opening and closure in said cover whereby perfume may be admitted to said enclosed compartment, the side wall forming the enclosed compartment having an inwardly depressed portion, a vent in said depressed portion 35 for said enclosed compartment, a nozzle in said enclosed compartment, said nozzle having its inlet end located near the bottom of the perfume in the enclosed compartment and its outlet end disposed within said depressed portion of the side 40 wall, a bellows secured in the second small compartment, a second nozzle secured to said bellows and having its outlet end located in said depressed portion in spaced relation to the first nozzle, a lid for the casing, and a sealing pad carried by said lid, said pad being adapted to enter 45 said depressed portion to seal the vent and outlets therein.

3. In cosmetic containers adapted to house a plurality of cosmetic commodities, a casing having 50 a hinged cover with the body of the casing partitioned to provide a plurality of compartments, said compartments including a compartment formed as a liquid perfume container having a closed top provided with a normally-closed filling opening, said compartment having a casing body wall active as a container wall with such wall having an external reentrant portion, and an open ended conduit within said compartment and having a nozzle portion projected 55 through said wall into such reentrant portion to permit external delivery of perfume from such compartment through said nozzle, said casing having a second compartment containing a manual air-forcing means including an air conduit the free end of which extends into said reentrant portion in juxtaposition to said perfume nozzle to constitute therewith a manually-operative atomizing unit permanently positioned for spray emission from the reentrant portion 60 zone when the cover is in open position.

4. An assembly as in claim 3 characterized in that the air-forcing means is in the form of a bellows formation dimensioned to be received within its compartment and having its upper 75 portion planar in form, said face being supported

for downward yielding to develop the atomizing air pressure, said face also including an air vent, whereby atomizing action is obtainable with the cover in open position by downward pressure on such upper face with the means completely housed when the cover is in closed position.

5. A cosmetic container comprising a casing adapted to contain toilet articles, a liquid compartment in said casing, a wedge shaped depression in a wall of said liquid compartment, outlet means for the liquid of said compartment terminating within said depression, atomizing means within the casing and cooperative with the outlet means for producing an atomized spray within the depression and external of the compartment, a vent for said liquid compartment located in said wedge shaped depression, a hinged closure for said casing, and wedge shaped seal-

ing means carried by said closure and adapted to enter said depression to seal said outlet means and vent when the closure is in closed position.
